RECORD CARRYING OR MEMORANDUM DEVICE

Filed June 20, 1930

UNITED STATES PATENT OFFICE

DE WITT C. HARRIS, OF LAKELAND, FLORIDA

RECORD CARRYING OR MEMORANDUM DEVICE

Application filed June 20, 1930. Serial No. 462,586.

The invention relates generally to record carrying or memorandum devices having means providing a surface of comparatively large area adapted to carry or have written thereon data of various kinds, the device being adapted to be collapsed to conceal the major portion of the record carrying surface and to occupy a minimum amount of space, and also being extensible to render 10 visible the entire record carrying surface.

An important object of the present invention is to provide a new and improved device of this character of sturdy and economical construction which may be easily moved by 15 the operator to its extended position.

In a device of this character it is often desirable to replace a part of the data carried on a record receiving surface and another object of the present invention is to 20 provide a device of this character adapted to receive a plurality of removable cards so as to facilitate replacement of various parts of the data carried by the device.

In the use of such a device the information 25 is usually written upon the record receiving surface while the device is suspended from a suitable support and another object of the invention is to provide such a device having a substantially rigid surface upon 30 which information may be written easily by the user.

Another object is to provide a collapsible device of this character having a plurality of plates connected together for movement 35 from a compact face to face relation wherein the faces of the intermediate plates are concealed, to an extended edge to edge relation wherein data on one face of each of the plates may be seen by the user.

Another object is to provide such an improved device capable of movement between extended and collapsed positions, together with means operable to hold the device in its collapsed position.

Another object is to provide a collapsible device of this character adapted for use as an abridged telephone directory or memorandum device and embodying novel means for securing the device to the transmitter of a telephone.

Another object is to provide such an extensible device having a plurality of substantially rigid plates each adapted to have a card removably secured thereto, and connected together in series, preferably by pivotal joints, whereby to permit the plates to be moved from a compact relation wherein they lie face to face to an extended relation wherein they are positioned with their corresponding card-carrying faces visible from 55 one direction, together with resilient means for drawing the plates to their compact relation.

Another object is to provide such a collapsible device formed from a series of pivotally connected members and having resilient means of a novel character for producing the desired pivotal movement of the various members.

Other objects and advantages will become 65 apparent from the following description taken in connection with the accompanying drawing, in which:

Fig. 1 shows a perspective view of the invention in its preferred form, attached to a telephone transmitter, and positioned in its extended relation.

Fig. 2 is a perspective view of the device in its compact relation.

Fig. 3 is an enlarged view of two of the 70 plates and a pivot pin which form a part of the device.

Fig. 4 is a vertical sectional view showing a formation of the attaching disk and the adjacent one of the plates.

Figs. 5 and 6 are sectional views taken along the lines 5—5 and 6—6 respectively of Fig. 3.

For purposes of disclosure the preferred 90 form of the invention is illustrated in the drawing and will hereinafter be described in detail as embodied in a form adapted for use as an abridged telephone directory, but it is to be understood that this disclosure is not 95 intended as a limitation of the invention to this form and to this particular use, it being contemplated that various changes might be made by those skilled in the art to adapt the invention to other forms and uses without de- 100

parting from the spirit and scope of the invention as defined by the appended claims.

In the preferred form chosen for disclosure the invention is embodied in a device intended 5 for use as an abridged telephone directory and having a plurality of flat members or plates 10 adapted to be mounted on a telephone transmitter 11, the plates being mounted for movement from a collapsed relation 10 shown in Fig. 2 to an extended relation shown in Fig. 1. In the collapsed relation the plates 10 are positioned closely adjacent to one another so that the device occupies a minimum amount of space and the faces of most of the 15 plates are concealed from view. The plates 10, when in their collapsed positions are preferably parallel to each other and in a face to face relation but when the plates are moved to the extended position shown in Fig. 1, they 20 assume an edge to edge relation wherein the corresponding faces of the plates are disposed in the same general direction and data carried on the faces of the plates may be readily seen by the user.

25 It will be seen that the aggregate area of all of the plates is quite large and since the plates may be made substantially rigid, the surfaces thereof are suitable for writing of memoranda thereon. For this purpose the 30 user may write on the upper surface of any one of the plates with one hand while that particular plate is grasped at its edges and supported by the other hand.

The mounting of the plates 10 for movement 35 between their compact and extended relations may be accomplished by any desired means and in the present case this result is obtained by connecting the plates directly to each other in series to permit relative movement of the plates. To effect the serial connection of the plates, each plate 10 has a plurality of suitable hinge lugs 12 formed on the opposite edges thereof and a plurality of pins 13 extend through the lugs to pivotally 40 connect the plates to each other in series. The axes of the lugs 12 on opposite edges of each plate 10 are offset in opposite directions from the plane of the plate (Fig. 5), to permit the plates to move into parallel relation to 45 each other.

50 While the plates 10 may be made of such a material and texture that records may be written directly on a permanent surface thereof, the present embodiment is such that 55 the plates 10 may removably receive a plurality of separate cards 15 upon which information may be written or printed. Thus, the device not only provides a memorandum receiving means, but also may be said to constitute a convenient filing device wherein 60 each plate 10 forms a record holder. Convenient access to the cards 15 held on the plates 10 may be had at any time by moving the plates 10 to their extended relation, yet 65 the device normally occupies only a minimum

amount of space since it may be moved to the compact bellows-like relation shown in Fig. 2 when not in active use.

Since the cards 15 provide a suitable writing surface, the plates 10 may be made of sheet metal thus simplifying the manufacturing operations necessary to produce the device. Thus, in the form shown, the hinge lugs 12 are formed by curling integral portions of the plates 10 as shown in Figs. 3 and 5. Integral portions of the plates 10 may also be used to provide a detachable mounting means for the cards 15 and in the present case an end flange 16 (Figs. 3 and 6) is formed at each end of each plate 10 and is bent reversely over one surface of its plate so as to overlie the card 15 when it is placed on the face of the plate 10. If desired, additional lugs 17 may be provided on the hinged edges of the plates 10 to overlie the edges of the cards 15 at points intermediate the ends thereof.

The present embodiment of the invention provides for convenient removal of the cards 15 from the plates 10 without mutilating the edges of the cards. This is accomplished by forming a pair of apertures 10^a in each plate 10, spaced from the outer edges of the plate so that the sharp point of a pencil or the like may be projected through the apertures 10^a from the rear of the plate to bend the card 15 outwardly and disengage it from the end flanges 16.

In order to automatically move the plates 10 to the collapsed or compact position shown in Fig. 2, resilient means is preferably provided acting between the various plates 10 to produce pivotal movement thereof toward their face to face relation. In the present case this is accomplished by utilizing the pivot pins 13 as torsional springs and as shown in Fig. 3, the pivot pin is of sufficient length to project at both ends beyond the outermost hinge lugs 12. These projecting ends of the pivot pins 13 are bent to provide arms 18 projecting at right angles to the axis of the pivot pins. When two of the adjacent plates have been connected together by projecting one of the pivot pins 13 through the hinge lugs 12, one of the arms 18 is positioned beneath the adjacent end flange 16 on one of the two plates. The other arm 18 is then rotated to apply a torsional stress to the pivot pin 13 and that arm 18 is then positioned beneath the adjacent flange 16 of the other one of the two plates. The torsional stress in the pivot pin 13 will then tend to move the two plates into a face to face relation.

The movement of the plates 10 to their extended relation produces additional torsional stress in all of the pivot pins 13 and when the plates are released by the user, they are snapped quickly back into their compact relation and the spring action of the pivot

pins acts as means for holding the plates in this position.

For the purpose of conveniently attaching the device to the telephone transmitter 11, two means are herein shown, which may be used independently or together as desired. The first of these two means comprises an apertured disk 20 connected to one of the end plates of the series, the aperture 21 in the disk being of sufficient size to slip over the enlarged outer end of the mouth piece 22 of the transmitter. At its outer edge the disk 20 has a plurality of resilient arcuate clips 23, extending in the same direction from the disk and arranged to engage the side edges of the transmitter to hold the disk in position against the forward face 24 thereof. The second securing means comprises a pair of resilient arcuate clamping arms 25, secured on the forward side of the disk 20 and arranged to embrace the sides of the mouth piece 22.

In Fig. 4 of the drawing it will be seen that the disk 20 and the adjacent plate 10 are integrally formed from a single sheet of metal with the plate and the disk substantially parallel and offset from each other by a connecting web 26 lying at right angles to the plate 20. With this construction a convenient pencil holder may be provided by forming a resilient finger 27 from the metal of the plate 10 and the web 26, this finger being arranged to extend upwardly through the aperture formed in the web 26 in cutting the finger therefrom. Thus, a pencil 28 may be positioned on the top of the web 26 and held in position by the finger 27 which clamps the pencil against the disk 20.

If desired, a small ring or disk 30 may be provided on the outer one of the plates 10 to provide a finger piece which may be grasped by the user to draw the plates to their extended position. Since this ring is visible at all times it may be used to carry a suitable advertising slogan. The disk 20 may also be used as a carrier for advertising material and for this purpose has a flange 20^a about its outer edge to overlie a card 15^a which conforms to the shape of the disk.

The card carried by the outer plate, to which the ring 30 is attached, usually carries advertising matter and it is, of course, desirable to prevent discoloring of this card. To avoid soiling of this card 15, the ring 30 is preferably offset forwardly from the plane of the adjacent plate 10 (Fig. 1) by means of a connecting web 31. Thus when the ring is grasped between the thumb and fore finger of the user, it will be impossible for the user's thumb to contact and soil the adjacent card 15.

From the foregoing description it will be apparent that the invention provides a collapsible device which is particularly advantageous for use as a carrier for frequently

used data. The fact that a stiff backing is provided for the record carrying surfaces enables the user to make notes readily on the device at any time.

Furthermore, the cards carried on the various plates may be removed and replaced at will so that the information in the device may be kept up to date at all times. Due to the fact that the cards may be removed quite readily, the device constitutes, in effect, a file, in which a number of records may be kept in conveniently accessible positions.

I claim as my invention:

1. A device of the character described comprising a plurality of plates pivotally connected at their edges to form an extensible series movable from a compacted face to face relation, wherein the faces of the intermediate plates are concealed, to an extended relation wherein the corresponding faces of all of said plates may be seen from the same general direction, means on the plate at one end of the series to mount the device on a support, means on the plate at the other end of the series for grasping that plate to move the plates to their extended relation, and spring means acting between the adjacent plates to draw said plates toward their compacted relation.

2. A device of the character described comprising, in combination, a plurality of substantially rigid flat plates pivoted together in series for movement from a first relation wherein said plates are positioned face to face to a second relation wherein said plates are positioned edge to edge with the corresponding faces of all of said plates visible from one direction, yielding means operable to move said plates from said second to said first relation, means on one of the end plates of said series for attaching the device to a support, and means on the other end one of said plates for grasping said plate to move said plates to their second relation.

3. A recording device comprising a plurality of similar flat members, means connecting said members together for movement of said members from a compacted relation wherein said members lie parallel and face to face to an extended relation wherein said members are positioned edge to edge with the record faces thereof disposed in the same general direction, resilient means acting to move said members from said extended relation to said compacted relation, means on one of said members for mounting the device on a support, and means on another one of said members adapted to be grasped by a user to move said plates to their extended relation against the force of said resilient means.

4. A record carrying device of the character described having a pair of plates, means on the edge of each of said plates providing an apertured hinge lug, a wire extending through the apertures in said lugs to pivot-

ally connect said plates to each other, said plates having end flanges formed thereon extending reversely over the faces of said plates to removably receive a card on each 5 of said plates and said wire having its ends extending beyond said hinge lugs and bent at right angles to the pivotal axis of the plates, one of said ends being positioned beneath the end flange of one plate and the 10 other of said ends being positioned beneath an end flange of the other plate.

5. A telephone directory device comprising, a record receiving means, an apertured disk connected to said means and adapted 15 to surround the mouth piece of the transmitter, a plurality of resilient clips projecting from the outer edge of said disk and adapted to engage the side edges of a transmitter to hold the device in position, and a pair of 20 resilient arcuate arms connected to said disk and adapted to embrace the sides of the mouth piece of a transmitter.

6. A telephone directory device having, in combination, a record receiving means, a 25 plate to which said means is connected, a disk connected to said plate and adapted to be mounted on the forward face of a telephone transmitter, and a resilient finger formed integrally with said plate and adapted 30 to clamp a pencil against said disk.

7. A device of the character described, having a plurality of plates connected together for movement from a compact relation to an extended relation, means on one 35 of said plates for mounting said device on a support and a finger piece on another of said plates by which said device may be moved to its extended relation, said finger piece being offset from the plane of the plate 40 to which it is attached.

8. A device of the character described comprising a plurality of plates pivotally connected together in series for movement from a compact face to face relation to an extended 45 relation wherein each of said plates has one face disposed in the same general direction, means on the plate at one end of the series to mount the device on a support, and a finger piece on the plate at the other end of the 50 series for moving the plates to their extended relation, said finger piece being offset from the plane of the plate to which it is attached.

In testimony whereof, I have hereunto affixed my signature.

55
